UNITED STATES PATENT OFFICE.

JAMES J. WOOD, OF FORT WAYNE, INDIANA, ASSIGNOR TO GENERAL ELECTRIC COMPANY, A CORPORATION OF NEW YORK.

WRINGER.

1,366,622.

Specification of Letters Patent. Patented Jan. 25, 1921.

Application filed February 27, 1920. Serial No. 361,824.

To all whom it may concern:

Be it known that I, JAMES J. WOOD, a citizen of the United States, residing at Fort Wayne, in the county of Allen, State of Indiana, have invented certain new and useful Improvements in Wringers, of which the following is a specification.

The present invention relates to wringers and specifically to power driven wringers, and has for its object to improve their construction.

For a consideration of what I believe to be novel and my invention, attention is directed to the accompanying description and claims appended thereto.

In the attached drawing, Figure 1 is a view in side elevation of a wringer embodying my invention; Fig. 2 is a longitudinal sectional view; Fig. 3 is an end view looking at the right hand end; Fig. 4 is a detail plan view of a portion of the left hand end, and Fig. 5 is a detail view showing the arrangement of nut and screw.

The frame of the wringer is made in three principal parts, a top member 5 which also forms a part of each side member and two housings 6 and 7 located on opposite sides which are secured to the top member. The top member and its depending end members 8 and 9 are cast as a unit thereby avoiding extra joints and decreasing the amount of machine work. These members are made of channel or U-shaped section which has the advantage of great strength for a given weight of metal, and the further advantage of forming a housing for certain of the working parts. From Fig. 2, it will readily be appreciated how fully the working parts are inclosed by the frame and its housing.

The two housings differ somewhat in construction due to the fact that one of them, in addition to completing one side of the frame, also forms a support for the wringer as a whole, the object being to provide an arrangement whereby the wringer can be adjusted or moved to different positions, angularly displaced, about a vertical supporting pivot. Considering first the one on the left hand side, it comprises front and rear vertically disposed walls and a connecting end wall 10. The top of the housing has a

finished surface which is rabbeted to the depending member 8 in the manner shown in Fig. 3. The parts are united by screws or bolts 11 which extend through ears 12, Fig. 55 4, formed on the lower end of the side member 8. The housing is also provided with an extension or arm 13 which forms the support for the wringer as a whole. The form of this extension may be varied to suit 60 the washing machine to which the wringer is to be attached, or the character of the driving mechanism. As shown it is tubular and terminates in a flange 14 which is adapted to be bolted to some part of the washing 65 machine that will permit of its being swung around on a vertical axis without interfering with the driving connection. The extension may be integral with or bolted to the housing depending upon the type of 70 washing machine to be equipped, or the driving mechanism.

Inside the housing is a sliding member 15 which is capable of vertical movements both in adjusting the tension on the rolls and 75 when the spring tension is suddenly removed, as in case of accident. This member is guided in its vertical movements by the front and rear walls of the housing. Its movements in the direction of the axis of the 80 rolls are limited by the end of the lower roll and by the cross-wall which carries the bearing of its shaft. The upper end of the member forms a seat for the lower end of the coiled compression spring 16, and to prevent the spring from being laterally displaced a centering device, such as a cylindrical extension 17 is provided which fits 85 inside of the spring. The member is also provided with a bearing 18 for the shaft 90 19 of the upper rubber covered roll 20. Below the bearing the member has two forks 21 which straddle the lower shaft 22 of the rubber covered roll 23. The purpose in forking the lower end of the member is to 95 give it substantial length of bearing surface without interfering with the lower shaft, and also to limit its sidewise movements. In this manner all danger of the member being cramped within the guiding surfaces 100 of the housing is prevented.

The inside of the housing is also provided

with a cross-wall 24 in which is located a bearing 25 for the lower roll shaft 22. It will be noted that the roll shaft bearings instead of being in the same plane are offset 5 one from the other, the purpose being to permit the use of relatively large bearings so as to decrease wear without the necessity of using unduly large and therefore more expensive rolls. On the roll shafts and outside 10 of the bearings are staggered gears 26 and 27, having square shaft openings, by means of which motion is transmitted from one roll shaft to the other. The lower shaft 22 projects through its gear for a short distance 15 and is also made square. Surrounding the square end of the shaft is a coupling 28, the latter also receiving the squared end of the driving shaft 29. This latter shaft is supported in a bearing 30 formed inside of the 20 extension 13 and it may be driven by some part of the washing machine or by a separate motor. By locating the bearings, gears and driving shaft within the housing and its extension all danger of the clothing of 25 the operator being caught is avoided.

The right hand housing 7 comprises front and rear vertically extending walls which are connected by the end wall 35. It is attached to the depending end of member 9 30 of the top part of the frame in the same manner as the left hand one above described. Inside the housing is a sliding member 36 which is a counterpart of the member 15 and carries the bearing 37 of the upper roll 35 shaft and forms a seat and centering device for the spring 38. The bearing for the lower roll shaft is supported in the end wall 35 and for this purpose the wall is provided with a boss 39 through which the squared 40 end of the roll shaft projects to receive a hand crank for rotating the rolls when for any reason it is necessary or desirable.

Both of the compression springs are vertically disposed and are inclosed on three 45 sides by the housings at their lower ends and by the depending channel members of the top frame at their upper ends. The springs are put under tension by a pair of horizontally extending levers 40 which have 50 pivots 41 carried by the top part of the frame. The outer end of each lever is provided with a depending conical projection 40^a which fits into the upper end of the spring and prevents the latter from being 55 laterally displaced. In other words, these projections form centering devices for the upper ends of the springs. The inner ends of the levers rest on the top of a nut 42, which is threaded on the vertical screw 43, 60 the latter having a hand wheel 44 by means of which the nut can be adjusted up and down. The front face of the nut is provided with a slot 42^c which receives a lug formed on the front depending wall of the top mem- 65 ber of the frame and prevents said nut from

turning but permits it to freely slide up and down.

The rear of the nut is provided with a slot 42^a, Fig. 5, which is closed at its upper end and is open at its lower end. Arranged to enter this slot is a pin 42^b carried by the rear depending wall of the top frame member. The purpose of the pin and slot is to provide a stop to prevent the nut from accidentally dropping out of the path of the end of the screw, if the handle should be inadvertently rotated sufficiently to disengage the threads of the screw and nut. The top and depending walls of the top frame member also serve as a housing for the levers and their associated parts by inclosing them on three sides. 80

On the top of the frame member is a boss 45 having a smooth cylindrical bore in which is located a sliding sleeve 46 which acts as an abutment or stop for the hand-wheel. The inside bore of the sleeve is smooth and slightly larger in diameter than the screw so as not to interfere with its turning movements. At its lower end sleeve 46 rests on a shoulder 46^a on post 43, so that 90 while the screw can turn freely in sleeve 46, the sleeve 46 cannot move axially on the screw. The outside of the sleeve is provided with an annular shoulder 47 with which the inner end of the quick releasing latch 48 normally engages. This latch is located in a side opening slot in the boss 45 and has a pivot 49. A coiled compression spring 50 normally holds the latch in the operating position shown. The lower end of the sleeve 100 is provided with such a taper that it will, if accidentally raised above the inner end of the latch 48, force said latch out of the way as the sleeve descends until the end or toe of the latch can engage the shoulder 47. 105 This is a desirable feature in that it facilitates assembling.

Assuming, for any reason, as for example, that the operator gets a hand caught in the rolls or the cloth gets jammed, the parts may 110 be quickly released by a downward movement of the latch lever. This moves the inner end of the latch out from under the shoulder on the sleeve with the result that the sleeve, nut and inner ends of the levers 115 drop, releasing the tension on both springs simultaneously. This in turn permits the upper roll, its bearings and their supporting members to move freely upward, the lower roll remaining in the normal position. The 120 upward travel of the levers 40, coiled springs and upper roll shaft under emergency conditions is sufficient to cause the staggered gears 27 to move out of engagement with the lower gears 26. This is important since it instantly restricts any pulling or drawing effect on the hand or cloth to the lower roll only and since the space between the two rolls is considerable, this 125 effect can be disregarded. 130

To reset the quick releasing mechanism the handle is first rotated in a direction to move the nut toward the lower end of the screw which is the normal direction of movement to decrease the spring tension. After the nut has been moved to about the bottom of its travel the handle, screw, nut and sleeve are raised by an upward pull on the handle until the inner end of the latch 10 is moved under the action of its lifting spring 50 into engagement with shoulder 47. The hand wheel is then rotated in the opposite or tension increasing direction until the nut reengages the inner ends of the levers, 15 after which continued rotation of the hand wheel in the same direction moves the levers and puts the springs under the desired compression. Or, if desired, the screw can be turned until nut 42 travels into engagement 20 with stop pin 42^b, after which further rotation of the screw in the same direction will cause the screw to move up (since the nut can move no lower) thereby raising sleeve 46, the turning movement being continued 25 until sleeve 46 is raised sufficiently high to permit the nose of latch 48 to drop under shoulder 47. However, the former method of resetting is more rapid than is the one usually followed.

I desire to emphasize the fact that the quick releasing means and the tension adjusting means are combined in one and the same structure thereby simplifying the apparatus as a whole and reducing the number of parts. The double spring and lever arrangement has the advantage of permitting the opposite ends of the rolls to independently adjust themselves to the quantity of cloth passing between the rolls. This arrangement also tends to cause the cloth to pass between the rolls in a straight path instead of a curved path as sometimes happens with a single spring construction.

The wringer rolls can be driven forward 45 or backward as desired by changing the direction of rotation of the driving shaft.

In order to convey the water squeezed out of the material by the rolls into suitable receptacles, a drain board or apron 51 is provided which is operative irrespective of the direction of movement of the rolls. This apron comprises a flat sheet of metal having turned up sides or edges 52. Extending through said sides at the middle thereof are 55 pivot pins 53, the latter being supported in axial alinement by the housings and below the rolls. By this arrangement the apron can be tilted in one direction or the other. To hold the apron in its adjusted positions a 60 pin 54 is mounted in one of the housings, and fastened to the apron is a flat spring 55 having a V-shaped projection 56 that is adapted to ride over the pin 54. When the pin is on one side of the projection the apron 65 is held in one inclined position and when on

the other is held in the opposite inclined position.

It is important, especially in power driven wringers, to be able to replace the rolls when worn or injured without returning the 70 wringer to the factory on the one hand, or requiring special tools or equipment on the other. To this end the housings are made removable as above described. The staggered gears 26 and 27 are fitted to slide on 75 their square ended shafts. The grooved collars 37 of the ball bearings are also arranged to slide on the roll shafts so that once the housings are removed, the rolls can be taken out and replaced by relative endwise 80 movements of the rolls and bearings.

I have illustrated ball bearings for the roll shafts because they can be made relatively narrow and of rather large diameter 85 but other forms of bearings can be employed if desired.

In accordance with the provisions of the patent statutes, I have described the principle of operation of my invention, together with the apparatus which I now consider 90 to represent the best embodiment thereof, but I desire to have it understood that the apparatus shown is only illustrative and that the invention may be carried out by other means.

What I claim as new and desire to secure by Letters Patent of the United States, is:—

1. In a wringer, the combination of a frame, a pair of rolls mounted thereon, means for driving the rolls, coiled springs 100 situated on opposite sides of the frame for forcing the rolls toward each other, a pair of levers pivotally supported on the top member of the frame, the outer ends of which act on the springs to stress them, and 105 a combined adjusting and quick releasing device carried by the frame, and comprising a nut and screw, said nut engaging the inner ends of the levers, and a releasable latch which normally supports the nut and screw 110 in operative position.

2. In a wringer, the combination of a frame, a pair of rolls mounted therein, means for driving the rolls, coiled springs 115 situated on opposite sides of the frame for forcing the rolls toward each other, a pair of levers for adjusting the spring pressure, the outer ends of which rest on the springs, means carried by said lever ends which engage the springs and hold them against lateral displacement, and a combined adjusting 120 and quick releasing device carried by the frame which engages the inner ends of said levers.

3. In a wringer, the combination of a 125 frame, a pair of rolls mounted therein, means for driving the rolls, bearings for one of the rolls, sliding members which carry the bearings and are guided by the frame, a combined spring seat and centering device 130

- for each member, a pair of levers carried by the top part of the frame, a centering device carried by the outer end of each lever, a pair of coiled compression springs, each of which engages a seat and is held top and bottom by the centering devices, and a combined adjusting and quick releasing device carried by the frame which engages the inner ends of said lever.
- 10 4. In a wringer, the combination of a U-shaped frame of channel section, said channel opening inwardly, a pair of rolls mounted in the frame, fixed bearings for the lower roll, sliding bearings for the upper roll, said bearings being inclosed in the frame, vertically disposed coiled compression springs which act on the sliding bearings and are inclosed on three sides by the channel frame, a pair of levers carried by the top member of the frame which act on the upper ends of said springs to compress them and are inclosed on three sides by said frame, an adjusting unit which acts on the inner ends of the levers and is partially inclosed by the walls of the top member, a screw for moving the nut which passes through the upper wall of the member, and a latch which normally holds the screw, nut and levers in position to stress the springs.
- 15 5. In a wringer, the combination of a frame comprising three principal members, an inverted U-shaped top member and two housing members on the sides, each housing member being bolted to a lower end of the top member and forming a continuation thereof, a means forming a part of one of the housings for supporting the wringer, a pair of rolls in the frame, gearing between the rolls, bearings for the shafts of the rolls
- 20 which are carried by the housings, vertically disposed coiled springs for exerting pressure on one of the rolls which are inclosed on three sides by the top member and housings, and lever means located within the top member for simultaneously adjusting the tension of the springs.
- 25 6. In a wringer, the combination of a frame comprising three principal members, an inverted U-shaped top member and two housing members on the sides, each housing member being bolted to a lower end of the top member and forming a continuation thereof, a means forming a part of one of the housings for supporting the wringer, a pair of
- 30 rolls in the frame, fixed bearings for the shaft of the lower roll which are mounted in the housings and are removable therewith, movable guide members carrying bearings for the shaft of the upper roll which are
- 35 separate from the housings but are guided by the walls thereof, a pair of adjusting levers within the top frame member which terminate at their outer ends in spring centering means, means for moving the inner ends of the levers to change the spring ad-

justment, and vertically arranged coiled compression springs which engage the centering means at the top and the guide members at the bottom, the guide members, bearings and springs being capable of being separated sufficiently to permit removal of the upper roll when one of the housings is removed.

7. In a wringer, the combination of a frame having a top member, a pair of rolls, spring means for pressing the rolls toward each other, and a combined tension adjusting means and quick release for the spring means comprising a nut which acts on the spring means, a screw which is threaded into the nut and provided with a head, a sliding sleeve which surrounds the screw and acts as an abutment for the head, and a releasable latch which normally holds the sleeve in position to take the reaction of the screw and when actuated releases the sleeve, nut and tension on the spring means.

8. In a wringer, the combination of a frame having a top member, a pair of rolls, spring means for pressing the rolls toward each other, a combined tension adjusting means and quick release for the spring means, comprising a nut which acts on the spring means and is held against rotation, a screw which is threaded into the nut and is provided with a head, a sleeve mounted in the top member of the frame, which acts as an abutment for the head, said sleeve loosely surrounding the screw and being provided with an external shoulder, and a latch which normally engages the shoulder and holds the sleeve in place and when released permits the sleeve to move freely.

9. In a wringer, the combination of a frame having a top member, a pair of rolls, spring means for pressing the rolls toward each other, a nut for adjusting the tension of the springs, a headed screw threaded into the nut, a vertically movable sleeve carried by the member and on which the head normally rests, said sleeve having a shoulder and a tapered lower end, and a pivoted latch which is biased to a position in engagement with said shoulder, the tapered lower end of said sleeve serving to push the latch to one side against the biasing force when the sleeve is inserted in said top member.

10. In a wringer, the combination of a frame, rolls and their shafts mounted in the frame, means for applying pressure to the rolls, a combined pressure adjusting means and quick release comprising a vertical screw, a sliding sleeve, a latch for normally holding the sleeve, a nut below the sleeve, means for holding the nut against rotation, and means for limiting the downward movement of the nut.

11. In a wringer, the combination of a frame, rolls and their shafts mounted therein, gears for transmitting motion from one

roll to the other, springs located at opposite ends of the rolls for forcing them toward each other, levers pivotally mounted on the top member of the frame for compressing the 5 springs, and a combined tension adjusting and quick releasing device which is carried by the frame and acts on the levers, said de-

vice when released moving out of the path of the levers to release the spring tension and permit the rolls to separate sufficiently 10 to disengage the said gears.

In witness whereof, I have hereunto set my hand this 24 day of February 1920.

JAMES J. WOOD.
